UNITED STATES PATENT OFFICE.

LEROY CHAMBERLAIN, OF WICHITA FALLS, TEXAS.

WEIGHT ELEVATOR FOR PULLING MACHINES.

Application filed April 22, 1926. Serial No. 103,871.

This invention relates to well drilling equipment and more particularly to portable types of drilling and pulling machines, and the primary object of the invention resides in the provision of an arrangement, coacting with the operating machinery of such machines in assembling and pulling rods and tubing, whereby to avoid the necessity of constant operation of the machinery and to thereby alleviate the burden imposed thereon.

With the foregoing and other objects and advantages in view, the invention resides in the salient features of construction and arrangement of parts hereinafter defined in detail and illustrated in the accompanying drawings wherein,

Figure 1 is a fragmentary representation of a casing pulling or drilling machine, in elevation.

Figure 2 represents a plan view of the usual drum construction.

Figure 3 is a vertical cross sectional view of the mast, showing the weight therein, and

Figure 4 is a modified exemplification of the manner in which the cable sheave may be mounted in the mast.

Heretofore, in assembling rods, tubing and the like in wells, it was necessary that the machinery be almost constantly operated both forward and reverse to maintain control of the lines in lifting the said rods and tubing into position and lowering the same.

With this in view, particular attention is directed first to Figure 1, in which a partial representation of a pulling machine 1 is shown, having a mast 2 of the usual tubular construction. This mast is collapsible upon the machine 1, from which position it is elevated for use to the position shown in the figure by suitable mechanism, not shown, nor forming a part of the present invention. A crown sheave 3 is mounted at the top of this mast, and about which a line 4 is passed, which latter has an end wound about the main drum 5, shown in Figure 2, while the opposite end thereof is used for handling tubing, rods, and the like.

In Figure 2, a plan view of the inclusive drum arrangement, the drum 5, not departing materially from the conventional drum structure, is fixed to the shaft 5^a, as is likewise the shorter drum 6, the latter being preferably situated outside the frame

1 of the machine. While no restrictions are intended as to structure, a ratchet 6^a is shown, particularly in Figure 2, which is also fixed to the shaft 5^a, and is engageable by the pawl 7, pivoted to the side of the frame 1. This pawl and ratchet mechanism, while in the present case is shown as being hand operated, may be of course modified so as to control the shaft 5^a, and drums 5 and 6 from other points on the machine by foot levers or other such means.

The line 4, which is the line used for handling various tools and the like, is wound upon the main drum 5 in a reverse manner to the position of the line 8 upon the drum 6, the reasons for which will be set forth presently.

Adjacent the top of the mast 2 a slot 9 is cut as shown, and in which a sheave 10 is adapted to be partially inserted, and held therein by a bracket 11. The line 8 is mounted over this sheave and a weight member 12 is swung thereon by a pulley 13, after which the line 8 is secured to an eye bolt 14 in the wall of the mast 2, opposite the pulley 10, as in Figure 3.

The weight member 12 is of course selected to outweigh the bodies attached to the line 4. Accordingly and in operation, the lines 4 and 8, being wound in a reverse manner about their respective drums 5 and 6, move in opposite directions, hence, an object attached to the operative end of the line 4 would move upward, simultaneous with a descending movement of the weight 12 within the mast 2, and vice versa.

A casing elevator or other type of grapple or hook may be applied to the end of the line 4, and in lowering casing, tubing, rods or such equipment into the well for example, the elevator is engaged with the body to be lifted, and when the pawl 7 is released from the ratchet 6^a, the weight 12, being of greater weight than the body, would obviously descend within the mast, thus elevating the body to a position whereby it may be accessibly urged into the hole by an attendant. This movement is entirely controlled by the weight 12, no operation of the motor, not shown, is required. However, in order to return the weight 12 to the top of the mast 2, the motor must be operated.

It is readily apparent that through the assembly shown, operation of the machinery is reduced to a minimum, thereby rendering

possible a material saving both in time and expense resulting from possible deterioration of machinery through constant operation under other conditions.

5. Figure 4 of the drawings illustrates a modified example of the structure described, in that the tying of the cable 8 to the eye 13 is dispensed with. In this latter instance, the position of the bracket 11 is reversed 10 and bolted as shown, thereby to dispose the pulley 13 nearer the center of the mast 2. The line 8 is then placed over the pulley as before and securely affixed to the weight member 12 as illustrated.

15. While specific details of structure and function have been set out herein, it is not desired that the invention be limited thereto, and that certain changes and modifications may be resorted to without departing from 20 the spirit and intent of the invention as set forth in the following claims.

I claim:

1. In a pulling and drilling machine; a weight elevator comprising in combination 25 with a hollow tubular mast and a pair of drums, a pulley mounted near the top of said mast, a line wound about one of said drums and passing about said pulley a weight supported by said line interiorly of 30 the mast; a second line wound in a reverse manner about the other of said drums and passing over a pulley on the top of said mast; means for holding said drums against rotation, and means for releasing said holding means to permit the said weight to be 35 lowered within the mast to elevate a body engaged by said second line.

2. In a pulling and drilling machine; a weight elevator comprising in combination 40 with a hollow tubular mast and a pair of drums; a pulley mounted on the top of said mast; a pulley mounted adjacent the top of said mast with its body extending partially within said mast; a cable having 45 one of its ends wound about one of said drums and passing over the first pulley exteriorly of said mast; a second line having one of its ends wound in reverse manner about the other of said drums and extending 50 over the second pulley and secured to the wall of said mast; a weight member having a pulley thereon arranged to ride on said second line intermediate said second pulley

and said securing point; means to hold said drums against rotation, and means to release 55 said holding means to permit said weight to descend within the mast to elevate a body carried by said first line.

3. In a pulling machine for rods and tubing, a weight elevator including in combination with a hollow mast and a pair of drums; a pulley on the top of said mast; a pulley below said first pulley having its body partially extending into said mast; a line wound about one of said drums and extending 60 over said first pulley exteriorly of said mast; a second line wound in reverse relationship about the other of said drums and extending over said second pulley; a weight carried by said second line interiorly of 70 said mast; a common holding means for said drums, and means to release said holding means, to permit said weight to descend, to exteriorly elevate an object carried by 75 said first line.

4. In a pulling machine for rods and tubing having a hollow mast structure; a weight member in said mast in combination 80 with a pair of rotatable drums; a pulley mounted on the top of said mast, and a second pulley mounted below said first pulley; a line passing about said first pulley having its end secured to one of said drums; a second line carried by said second pulley having its end secured to the other of said 85 drums and arranged to support said weight member interiorly of said mast; and means to control the movement of said drums to permit said weight to descend in said mast to 90 elevate an object on said first line.

5. In a pulling machine for rods, tubing and the like, having a hollow mast structure in combination with a pair of drums; a weight interiorly of said mast structure; a line supporting said weight and having its 95 opposite end wound about one of said drums; a second line reversely wound about the other of said drums and extending over the top of said mast, and means to control the movement of said drums to permit said 100 weight to be lowered within said mast to effect raising of said second line to elevate an object carried thereby.

In testimony whereof I affix my signature.

LEROY CHAMBERLAIN.
